UNITED STATES PATENT OFFICE.

JOHN H. RUSHTON, OF CANTON, NEW YORK.

COMBINED MAST HEAD AND FOOT GEARS.

SPECIFICATION forming part of Letters Patent No. 352,713, dated November 16, 1886.

Application filed June 19, 1886. Serial No. 205,659. (No model.)

To all whom it may concern:

Be it known that I, JOHN H. RUSHTON, of Canton, in the county of St. Lawrence and State of New York, have invented a new and 5 Improved Mast Head and Foot Gear, of which the following is a full, clear, and exact description.

The object of this invention is to save lashing the blocks, &c., of mast-head and mast-foot gear to the masts of sailing craft of different kinds, and to secure a "fixing" or gear that will allow the sail, spars, and cordage to turn freely and without fouling.

The invention, which will be found very 15 useful on canoes and small craft, but which may also be used on crafts of different kinds, of any size, consists in swiveling devices applied to the head and foot of the mast, the same being made free to rotate about or around 20 the longitudinal axis thereof, and having the blocks through which the halyards or other ropes run attached to them in a free or loose manner; also, when necessary, provided with rings or eyes for certain or special cords or 25 ropes controlling the sails, substantially as hereinafter described. The blocks attached to these swiveling devices or carriers may either be single or double ones; or there may be more than one block to each carrier, and the 30 blocks themselves have one or more sheaves, according to the requirements of the craft or its rigging.

Reference is to be had to the accompanying drawings, forming a part of this specification, 35 in which similar letters of reference indicate corresponding parts in all the figures.

Figure 1 represents a side view of a canoe sail and rigging in part, with mast having my invention applied; Fig. 2, a view in perspective, upon a larger scale, of the mast with 40 the same gear applied to the head of it, as shown in Fig. 1; and Fig. 3, a perspective view of the foot-gear of said mast. Figs. 4 and 5 are side views of portions of the mast, showing, respectively, the head and foot gears thereof, with the blocks forming parts thereof as containing two sheaves instead of one. Fig. 45 6 is a view in perspective of the gear used at head of the mast, fitted with two blocks in-

stead of one; and Fig. 7, a side view of the gear 50 at foot of the mast, also having two blocks to correspond.

The mast head and foot gears shown in the several figures of the drawings in no wise differ from each other except in the character of 55 block used, which may either be a single one with single sheave, as shown in Figs. 1, 2, and 3, a single block with two sheaves, as in Figs. 4 and 5, or two independent blocks, as shown in Figs. 6 and 7, according to the requirements 60 of the craft or its rigging, so that it will only be necessary here to describe more particularly the mast head and foot gears shown in Figs. 1, 2, and 3, which will now be done.

A indicates the mast, B the boom, C the sail, D the batten, and E the yard, of a canoe craft. For instance, b indicates the halyards, c the reef-lines, and d the lazy-jacks.

G is the gear at foot of the mast, the same 65 consisting of a ring, band, or block carrier, e, 70 fitted to freely swivel or rotate around the mast between suitable collars or projections, f, secured to the mast. This ring or band e has loosely or freely attached to it for independent movement, as required, a sheave-block, g, for the halyards b to run through, and also has loosely attached to it a ring, h, 75 for the reef-lines c.

H is the gear at head of the mast, consisting 80 of a flat angularly-bent band or block carrier, i, constructed to lay over the top of the mast and to project laterally downward in relation thereto, and fitted to freely swivel or rotate about or around a stud or bolt, k, on the top 85 of the mast in a central or axial line therewith. This band i has also loosely or freely attached to and pendent from it at or near its lower end, for independent movement, as required, a sheave-block, l, for the halyards to run through, and has also, if desired, a projecting eye, m, for the lazy-jacks d.

The head-gear H, constructed as described, provides for the use of a shorter mast, and, combined with the foot-gear G, allows the sail to revolve on the mast without fouling the 90 ropes. Double or single blocks can be used on the head-gear and double or single or several blocks on the foot-gear.

Having thus described my invention, what I claim as new, and desire to secure by Letters Patent, is—

1. In a mast-head gear for sailing craft, the 5 head-gear *H*, having a bent band or block carrier, *i*, adapted to swivel or rotate upon top of the mast and to project laterally downward in relation therewith, and provided at or near its lower end with one or more loosely or freely attached sheave-blocks, *l*, in combination with a mast-foot gear having one or more freely-attached blocks and halyards, substantially as specified.

2. In combination with a mast-head gear 15 fitted to freely swivel or rotate on and around the upper end of the mast, the foot-mast gear *G*, having a ring, band, or block carrier, *e*, adapted to encircle and to swivel or rotate around the lower portion of the mast, and provided with one or more loosely or freely attached sheave-blocks, *g*, together with means connecting said mast-head gear and mast-foot gear, substantially as described.

3. The freely swiveling or rotating mast-head gear provided with a projecting eye, in 25 combination with the freely swiveling or rotating mast-foot gear provided with a reef-line ring, and halyards connecting the same together, substantially as and for the purpose set forth.

4. The combination of the mast *A*, the ring-like foot-gear *G*, having one or more freely-attached blocks, *g*, the stud or bolt *k* on top of the mast, and the downwardly-overlapping head-gear *H*, adapted to freely swivel or 30 rotate around the upper end portion of the mast, and provided at or near its lower end with one or more loosely or freely attached sheave-blocks, *l*, and the mast-foot gear having a reef-line ring, together with halyards connecting 35 the said foot-gear and mast-head gear, substantially as specified.

JOHN H. RUSHTON.
